UNITED STATES PATENT OFFICE

PAUL WRIGHT, OF BIRMINGHAM, ALABAMA

BOILER

Application filed May 2, 1928. Serial No. 274,624.

This invention relates to boilers of the type described in my U. S. Patent No. 1,437,790, dated December 5, 1922.

The object of the present invention is to secure an efficient generation of steam and its separation from the water, and at the same time provide a compact association of the component parts, thus effecting economy in the construction of the furnace and its setting. With this object in view, the invention consists in a novel arrangement of drums and boiler tubes and their combination with each other and with the furnace, together with a system of baffling for directing the heated gases over and around said tubes.

One form which the invention may assume is shown in the accompanying drawings, but it is to be expressly understood that said drawings are for the purpose of illustration only and are not designed to define the limits of the invention, reference being had to the appended claims for this purpose.

In the drawings, in which similar reference characters designate corresponding parts—

Fig. 1 is a vertical longitudinal section of a boiler embodying the invention;

Fig. 2 is a horizontal enlarged section of the boiler and furnace on line X—X, Fig. 1; Fig. 3 is a vertical longitudinal section of a modification of the invention; and

Fig. 4 is a fragmentary view showing the method of connecting certain of the tubes to the water drum.

Referring particularly to Figs. 1 and 2, the boiler proper comprises a supported bottom or mud drum 1, a suspended front or water drum 2 and a supported top or steam drum 3, in the relation that the front drum is forward of and above the bottom drum, the top drum is backward of and above the front drum and also forward of a vertical plane midway between the front drum and the bottom mud drum. These drums are connected

by three principal banks of tubes having the relation that (as shown in Fig. 1) the first bank 5 connects the upper left hand quadrant of the rear drum 1 with the lower right hand quadrant of the front drum 2 thereby providing a gradually ascending bank between

the two drums over the fire box; the second bank 6 connects the upper right hand quadrant of drum 2 with the lower left hand quadrant of the top drum 3, thereby providing an ascending bank generally in a vertical direction, although this tube bank 6 may be inclined slightly forward or slightly rearward (from the vertical) to suit construction advantages that govern; and a third bank 7, considerably longer than the first and second banks, which, with tubes 8, connects the lower right hand quadrant of the top drum 3 with the upper right hand quadrant of the bottom drum 1, thereby providing a descending inclined bank. The first bank 5 is preferably somewhat longer than the second bank 6, but may be of the same length or approximately so.

Referring further to Figs. 1 and 2, the boiler comprises, in addition to banks 5, 6 and 7, banks of furnace tubes as follows:

Tube bank 20 connecting a water header 15 with front drum 2; tube bank 21 connecting a water header 19 with the front drum 2; and tube banks 22 on either side of the furnace, connecting water headers 17, 17 with front drum 2. A feed water supply for water headers 15, 17 and 19 is provided by means of pipes 13 leading from bottom drum 1, thence through pipes 14 to header 15, through pipes 16, 16 to headers 17, 17, and thence through pipes 18, 18 to header 19, see Fig. 2. By this means a main circulating system is provided that consists of bottom, front and steam drums triangularly disposed and communicating in series through interposed banks of tubes, and a secondary circulating system comprising water headers communicating in series through furnace banks of tubes with the main system at the front drum, pertaining to which the arrows on the drawings indicate the paths and directions of flow.

The advantages obtained in circulation and steam disengaging capacity of the main circulating system are described in my patent aforesaid. The secondary circulating system possesses the following advantages. The water tubes 20, 21 and 22 are directly exposed in the hottest portions of the furnace and, being subjected to radiant heat, they more ef-

55

60

65

70

75

80

85

90

95

100

ficiently generate steam at a higher rate per unit of exposed surface than tubes in other parts of the boiler; an unfailing supply of feed water in ample quantity is provided for 5 this secondary circulating system; the generated steam from this secondary system is conveyed without obstruction or constricted flow, into the main circulating system's up-
cast bank of tubes 6 preparatory to dis-
10 gaging in the top drum; adequate provision is made to care for extreme expansions and contractions of the furnace tubes; and quick facilities for cleaning the tubes by turbining are afforded as well as accessibility to all
15 parts.

It will be seen from Fig. 1 that the water supply for the boiler proper is fed into drum 1 through pipe 12, and that from drum 1 the feed pipes 13 supply water to the headers 20 15, 17 and 19. Thus almost the entire water content of the boiler proper is available to serve pipes 13 and with considerable hydro-
static head, this head being proportionate to the difference in elevation of the headers 15,
25 17 and 19 and the water level in top drum 3. As a result, an extremely rapid generation of steam in the furnace tubes is accomplished without endangering them (from overheating) by a lack of an unfailing supply of feed
30 water in ample quantity.

As the additional furnace tubes deliver their steam and water into drum 2, from whence same passes naturally upward and through a plurality of tubes into the top or 35 steam drum 3, the passage or flow is accomplished smoothly without belches or spouts and hence the steam is disengaged with the advantage of a minimum moisture content. The passage of steam from the furnace tubes
40 of the secondary circulating system through bank 6 serves to further accelerate circulation through the main circulating system, and this is advantageous in increasing steam generation. The furnace tubes are subjected to
45 a wide range of temperature changes between conditions when the boiler is idle and when it is in operation, and therefore they must properly accommodate movement due to ex-
pansion and contraction. As is disclosed in
50 my patent aforesaid and my improvements thereon herein specified, the top drum 3 is fixed and rests on a beam 30 supported on columns 29 and 31; the bottom drum 1 is yieldingly supported on inclined brackets 32
55 attached to columns 31; drum 2 is suspended by the boiler tubes 5 and 6 and yet its guided movement caused by expansion or contraction is very slight, due to the compensating movement of drum 1 and the construction
60 just described. Moreover the header 15 is supported on saddles, as shown, and the connecting tubes 20 are of such shape and length as to easily accommodate any expansion or
65 contraction movement by bending; tubes 21 serve to suspend header 19 which is free to

move; headers 17 are supported on saddles 15', and tubes 22 leading therefrom are curved at the upper and lower portions so as to easily accommodate such movements by bending; and all connecting pipings have bends affording necessary movement. These features eliminate unduly strained tubes as well as leaky joints at the headers. The arrangement for furnace tubes 22 to enter drum 2 provides quite an easy means for turbining downward for internal cleaning, as this can be done from within drum 2 and thereby save the extra time and work that would be occasioned if the handhole plates opposite tube ends in headers had to be removed for
70 cleaning these tubes.

The type of furnace illustrated in Figs. 1 and 2 is arranged for a multiple retort forced draft underfeed stoker 37; but the invention is not limited to a furnace employing such a stoker, since the furnace and circulating system may be adapted for other types of stokers or hand firing or to arrangements for burning pulverized fuel. Moreover one of the headers with its bank of tubes might
75 be omitted, for example header 19 with its tubes 21, without departing from the invention.

This definite relation of drums and tubes lends itself to an improvement in baffling that forms a part of the present invention. By reference to Fig. 1 it will be seen that the row of tubes 8 serves to support the principal refractory baffle 26 that directs the furnace gases successively around the tube banks 90 from the firebox to the exit. A novel feature is the arrangement of tubes 8, which extend from the upper side of drum 1 to the lower side of drum 3, thereby providing a continual upward path of flow for the steam 95 and water within these tubes. This flow is upward since the baffle 26 supported on tubes 8 exposes these tubes to gases of a sufficiently high temperature to generate steam which therefore flows to drum 3 for disengaging. These tubes 8 constitute a support for the refractory baffle tiles 26, and these tiles tend to slide downward on the inclined tubes and hence always remain tightly jointed. Furthermore this inclined position of the baffle
100 tiles facilitates the sweeping downward of any dust brought from the furnace by the flowing gases, thereby assuring clean baffles that are tight and yet free from lodgment of dust. The shape of tubes 8 with reference to tube bank 7 provides room for an access door in the side wall between tubes 8 and bank 7, thereby permitting all baffle tiles to be inspected or handled in or out of the
105 setting.

In positioning tubes 8 with relation to the bank of tubes 7, it is advantageous in certain sizes of boilers that tubes 8 be arranged about parallel to the adjacent tubes in bank
110

7, thereby affording a larger triangular space between tube banks 5, 6 and 7 to accommodate a superheater of larger proportions. In such case it is desirable to omit one tube 8 of the row for the purpose of inserting or removing the baffle tiles, thus avoiding the necessity for an access door in the walls. The net distance between tubes 8 and their adjacent tubes in bank 7 must exceed twice the thickness of the baffle tile for proper passage clearance of the tile in or out. Another valuable feature of the baffle arrangement described is the simplicity with which the opening for gas passage at the upper end of the baffle may be changed in size merely by putting on or taking off some of the tiles 26 on tubes 8. Furthermore a minimum loss in drafts results can be secured by proper proportioning of the gas passage and with a minimum of abrupt turns in direction of flow. If necessity arises for removing and replacing any of the boiler tubes, the simplicity of this baffling and its easy removal and replacement will save time of boiler operation and work expenses involved in changing a tube.

This arrangement of baffle 26 on tubes 8 serves to direct the heated gases over a superheater element 36. The novel arrangement of drums and tubes provides ample space for the superheater 36, as shown in Fig. 1, and this general position of superheater with reference to the gas passage is quite advantageous because the gases arrive in said position at a suitable temperature for efficient and successful superheat transfer since they have first passed through tube bank 5, which serves to properly temper the gases, thereby preventing the superheater tubes from possible over-heating.

As shown in Fig. 1, the superheater 36, within the triangular space between the boiler banks 5, 6 and 7, is connected to the saturated steam header 36' and the superheated steam header 36'', both of which are located without the heat zones and adjacent the front wall. But the location of the saturated steam header and the superheated steam header adjacent the front wall is shown for illustrative purposes only, since these two headers may be placed outside of and adjacent any other wall or walls and connected to the superheater 36, if the particular construction makes this desirable as here shown, the superheater 36 is supported within the furnace on the drum 2 and on a bracket 5' attached to the bank of tubes 5.

The relation of drums, tubes, headers and pipings comprising the main and the secondary circulating systems herein described, together with the supporting frame, provide for certain improvements in the furnace setting. The furnace lower front wall 34 may have its lower portion arranged for a stoker 37 as shown in Figs. 1 and 2, or for other

forms of furnace firing. The upper portion of wall 34 terminates between front drum 2 and the supporting frame beam 33. Since drum 2 has only a slight movement (generally downward) due to expansion caused by temperature changes, it serves, with the fixed beam 33, to provide a lateral support for upper portion of wall 34. The upper front wall 35 is supported in fixed position by beam 33 in such a way as to form a lap joint contact with lower front wall 34. This arrangement of lower front wall 34, with upper front wall 35 provides a useful expansion joint yielding to upward or downward movement of the lower wall, while maintaining a gas tight contact between the two. A suitable plate 34' caps off wall 34 to prevent dust from lodging between the drum and wall. Thus lower wall 34 may yieldingly expand or contract and have its alignment maintained by the novel arrangement described. The life of the wall 34 is thereby greatly prolonged.

The furnace setting arranged with the secondary circulating system of furnace tubes 20, 21 and 22 provides a firebox that will permit a much more rapid heat release from fuel burned therein than would be the case without employing these tubes in group or singly. Therefore these furnace tubes serve to increase the heat resistance of the walls and prolong the life of the furnace setting, and provide an efficient steam generating adjunct to the main boiler. The furnace so arranged may be advantageously employed to use pulverized coal, oil or gas as fuel, to burn at relatively high temperatures not practical if the said furnace tubes with secondary circulating system were omitted.

In Fig. 3 is shown a modified form of the boiler and setting and similar reference characters designate corresponding parts shown in Fig. 1. The modified boiler comprises a supported bottom drum 1, a suspended front drum 2, a supported top drum 3, a supported auxiliary top drum 4, in the relation that the front drum 2 is forward of and above the bottom drum 1, the top drum 3 backward of and above the front drum 2 and also forward of the bottom drum 1, and the auxiliary drum 4 is above the front drum 2 and forward of top drum 3. These drums are connected by four banks of tubes having the relation that the first bank 5 connects the upper right hand (as shown in Fig. 3) quadrant of the bottom drum 1 with lower left hand quadrant of front drum 2, thereby providing a gradually ascending bank between the two drums over the firebox; the second bank 6 connects the upper left hand quadrant of front drum 2, and the lower right hand quadrant of the top drum 3, thereby providing an ascending bank generally inclined slightly backward from the vertical; the third bank 7, considerably longer than the first and second banks, con-

nects the lower left hand quadrant of the top drum 3 with the upper left hand quadrant of the bottom drum 1, thereby providing a descending inclined bank; the fourth bank 9 connects the upper right hand quadrant of front drum 2 with bottom portion of drum 4, thereby providing an ascending bank of tubes either vertical or approximately parallel to adjacent bank 6; a water circulating pipe or pipes 11 connecting the lower portions (or water spaces) of drums 3 and 4, and steam circulating pipes 10 connecting the upper portions (or steam spaces) of drums 3 and 4. The first bank 5 is preferably somewhat longer than second bank 6, but they may be the same length or approximately so. In this way a main circulating system is provided that consists of a bottom or mud drum, a front or water drum, a top or main steam drum and a top auxiliary water and steam drum.

In this modification the baffles 26 supported by tubes 8 are similar to those shown in Fig. 1 and there is introduced another baffle 28 to deflect the furnace gases across and over bank 6; also an optional baffle 27 may be placed on bank 5 adjacent to drum 2 as indicated. The supporting frame for the modified boiler is similar to the arrangement described for boiler shown in Fig. 1, drum 4 being supported on beam 30.

Referring to Fig. 3, the secondary circulating system is partially indicated by feed circulating tubes 23 from drum 1 with furnace steam generating tubes 24 ascending into drum 1 and similar tubes 25 ascending to drum 2. This arrangement of the secondary circulating system suits furnace chamber designs for various fuels or methods of firing.

40 The maximum desirable length of water tubes of any given size governs the maximum amount of heating surface obtainable for a given number of such tubes in the boiler. In the present case the longest tubes occur in the rear of bank 7, and obviously, with bank 6 slightly inclined backward from the vertical, are advantageous in boilers of larger sizes, since it enables a relative increase in the lengths of banks 5 and 6.

50 Where the ratio of tube heating surface to water storage drums is relatively large per section of boiler, as illustrated by the modified boiler, Fig. 3, it is desirable to proportion the water and steam space at the top of the boiler to suit. This increased capacity is accomplished by providing the auxiliary drum 4 and connecting it with drum 3 by circulating tubes 10 and 11. In high pressure designs especially, the two top drums 60 are more economical in cost than a single drum of equivalent volume and the two are more easily handled and erected.

While for the purpose of describing the invention the construction shown in the drawings has been described with particularity, it

is to be understood that the invention is not limited to the precise construction illustrated, since various modifications may be made and some of the parts omitted without departing from the spirit of the invention, and the appended claims are intended to cover such variations and modifications as fall within the terms of said claims.

What is claimed is:

1. In a steam boiler, the combination of mud, water and steam drums, banks of tubes connecting said drums in a closed circuit, a plurality of headers exterior to the furnace, tubing connecting the mud drum with each header, and a bank of tubes extending within the furnace from each header directly to the water drum.

2. The combination of a furnace, a boiler within the furnace, said boiler comprising mud, water and steam drums and banks of tubes connecting said drums in a closed circuit, two headers exterior to the furnace, piping connecting said headers, piping leading from the mud drum to one of said headers, and banks of tubes extending from each header into the furnace and directly connected to the water drum.

3. The combination of a furnace, a boiler within the furnace, said boiler comprising mud, water and steam drums and banks of tubes connecting said drums in series, four headers exterior to the furnace one adjacent each of the four walls thereof, piping connecting the rear and the side headers with the mud drum, piping connecting the side headers with the front header, and banks of tubes leading from each header into the furnace and connecting directly with the water drum.

4. A steam boiler comprising mud, water and steam drums in series communication through interposed banks of tubes, said drums being in triangular arrangement with the mud drum positioned to the rear and below the horizontal level of the water drum and the steam drum positioned above the water drum and in front of a vertical medial plane between the mud and water drums, in combination with a superheater having two headers exterior to the front furnace wall, and tubing leading from one header across the water drum into the triangular space between said banks of tubes and thence to the other header.

5. The combination of a furnace front wall having independently supported upper and lower sections provided with an expansion joint therebetween, with a suspended boiler drum bearing against the inner face of said lower wall section adjacent said joint.

6. The combination of a furnace having a front wall divided into upper and lower sections, a bottom support for the upper section, a bottom support for the lower section, the top of said lower section overlapping the bot-

tom end of said upper section on the inside of the latter, and a suspended boiler drum bearing against the inner face of said lower section adjacent said overlap.

5 7. The combination of a furnace having a front wall divided into upper and lower sections, a bottom support for the upper section, a bottom support for the lower section, the top of said lower section forming an overlapping joint with the bottom of said upper section, a bearing plate on the interior of said lower wall section adjacent said joint, and a boiler drum bearing against said plate.

8. A steam boiler comprising, mud, water and steam drums in series communication through interposed banks of tubes, said drums being in triangular arrangement with the mud drum positioned to the rear and below the horizontal level of the water drum, 15 and the steam drum in a plane above and to the rear of the water drum, the lower row of the bank of tubes connecting the steam and mud drums extending from said mud drum to a point approximately opposite the middle 20 portion of the bank connecting the water and steam drums and then parallel with said last-named bank to the steam drum, a baffle supported by said lower row of tubes, a baffle extending transverse to and supported by the 25 bank of tubes between the water and steam drums and in substantial alignment with said last named baffle, a fourth drum above the water drum and in the same horizontal plane as the steam drum, piping connecting the 30 lower parts of the steam and fourth drums, piping connecting the upper parts of said last-named drums, and a bank of tubes between the water drum and said fourth drum.

9. The combination of a furnace, a boiler 40 within the furnace, said boiler comprising mud, water and steam drums in a closed circuit, four headers below the level of the mud drum and exterior to the furnace one adjacent each of the four walls thereof, piping 45 leading from the upper half of the mud drum to the rear header and to the two side headers, piping connecting each side header with the front header, and a series of pipes leading from each header through the wall of the furnace 50 and upward along the interior face of the wall and to the water drum.

10. The combination of a furnace, a boiler within the furnace, said boiler comprising mud, water and steam drums, banks of tubes 55 connecting said drums in a closed triangular circuit, connected horizontal headers extending along the four walls of the furnace below the level of the mud drum, piping connecting one of these headers with the upper 60 half of the mud drum, and four series of tubes, one from each header, extending vertically along the inner face of the furnace walls and thence to the water drum, whereby a secondary circulating system is provided.

65 11. In a furnace, the combination of mud,

water and steam drums, banks of tubes connecting said drums in a closed triangular circuit, the bank connecting the mud and water drums extending across the fire box, a stack leading from the furnace adjacent the lower end of the tube bank connecting the steam and mud drums, a saturated steam header and a superheated steam header exterior to the furnace chamber, superheating piping from the former header into the triangular space between said drums and then to the latter header, said piping being supported by the tube bank connecting the mud and water drums, and a single baffle extending in an upwardly-inclined direction from the mud drum and between the superheater piping and the main portion of the tube bank leading from the steam drum to the mud drum, whereby the tube banks are protected from stack moisture and the superheating piping and the tube bank between the mud and water drums are subjected to direct radiant heat.

In testimony whereof I have signed this specification.
